Att'y's.

UNITED STATES PATENT OFFICE

2,023,461

FLOAT STRUCTURE

Charles A. Butler, Okmulgee, Okla.; Sadie A. Butler administratrix of said Charles A. Butler, deceased

Application March 31, 1932, Serial No. 602,348

6 Claims. (Cl. 137—104)

This invention relates generally to improvements in float systems for pneumatic pumping such as described in my Letters Patent No. 1,839,140 granted December 29, 1931.

5 The invention relates particularly to a float structure for a pneumatically actuated pumping system such as shown in my Letters Patent No. 1,937,423 granted November 28, 1933.

An object of the invention is to provide a float 10 capable of resisting high pressures and rapid fluctuations of pressures.

Another object of the invention is to provide a float of the above type which consists of a plurality of rigidly assembled units which operate 15 independently.

The above and other objects of the invention will in part be obvious and will be hereinafter more fully described.

In the drawing: 20 Fig. 1 is a side elevation partly in section of a three-unit float.

Fig. 2 is a top plan view of the same.

Fig. 3 is a horizontal section taken along the line 3—3 of Fig. 1.

25 Fig. 4 is a side view of a float reinforcing member.

In my aforesaid Letters Patent No. 1,937,423, there is shown and described a pneumatically actuated pumping system which may be employed 30 for pumping liquids from great depths, as from oil wells and the like. The present invention relates to the float structure which is employed in the above patent for actuating the valve body.

As shown in the accompanying drawing, the 35 float is constructed of three units which may be independent so that the number of units employed may be changed according to the lift desired or necessary for actuating the structure which is controlled thereby. Each of these units 40 has a pair of vertical walls 110, each of said vertical walls being formed as a circular arc concentric with the adjacent wall of the casing or other containing structure, so that the float may be mounted with either side toward the containing structure. These side walls 110 are closed 45 at the top by a horizontal partition 111 which is preferably secured by welding to the side walls. An intermediate stiffening plate 113 is provided between the side walls 110 and is formed from a

50 single sheet of material with oppositely directed elevations 114 which are formed by locally depressing portions of the stiffening plate. This stiffening plate is inserted into the particular unit until it rests against the closing partition 55 111 of the unit, and then it is welded in this po-

sition. Each of the lower units is provided at its top with four integral connecting fingers 115 which are slightly offset inwardly a distance corresponding to the thickness of the material of the side walls 110, so that during assembly an upper 5 unit may be slid over the fingers 115 of the next lower unit and secured thereto by spot welding or the like. In this way each of the units has a substantially open bottom, so that it cannot become liquid-logged during operation and can respond immediately to changing conditions of pressure even though these changes be rapid, by permitting an immediate balancing of the pressures.

This float structure, being responsive to the 15 liquid level in the casing or other enclosing structure, operates in the manner described in my aforesaid Letters Patents.

It is obvious that the invention is not limited solely to the illustrated form but may be modified 20 in many ways within the scope of the appended claims.

Having thus described the invention, what I claim as new and desire to secure by Letters Patent, is:— 25

1. A float including connected vertical walls and a transverse reinforcing wall for dividing the float into a plurality of compartments, each compartment having an opening at the bottom thereof. 30

2. A float including externally convex vertical walls a top closure connecting and sealing said walls, and a substantially vertical reinforcing wall extending radially with respect to and bracing the convex walls, said float being open at its 35 bottom.

3. A float unit comprising a pair of externally convex vertical walls, at least a portion of the surface of each wall being of radius greater than half of any horizontal dimension of the float 40 unit, and a substantially vertical internal reinforcing wall arranged radially with respect to said convex walls and engaging the same at said portion of each thereof.

4. A float as in claim 1, in which the reinforcing wall is a sheet of substantially rigid material with a plurality of oppositely directed depressions out of its plane. 45

5. A float unit comprising vertical walls, a top closing wall, said unit having an open bottom, 50 and a plurality of attaching lugs integral with the vertical walls and extending above said top wall and offset inwardly substantially the thickness of the vertical walls, whereby the lugs of one unit may be inserted within the open bottom of 55

another unit and secured to the vertical walls thereof to form an assembly of a plurality of units.

6. A float unit comprising vertical walls and a top closing wall and having an open bottom, and a plurality of attaching lugs each integral with

a wall of said unit for connection to a corresponding wall of an adjacent vertically aligned unit, said lugs being spaced apart horizontally for providing access of fluid to the internal space of the upper unit.

CHARLES A. BUTLER.
